CAP

Byron Quinby Jones, Fort Humphreys, D. C.

Application June 30, 1939, Serial No. 282,173

5 Claims. (Cl. 2—195)

(Granted under the act of March 3, 1883, as
amended April 30, 1928; 370 O. G. 757)

The invention described herein may be manufactured and used by or for the Government for governmental purposes, without the payment to me of any royalty thereon.

This invention relates to improvements in caps of a style or type such as is customarily worn by men in the military and other uniformed services, and the objects of the improvements are:

First, to provide a collapsible military type cap having substantially all of the advantages of the conventional stiff, drum-like service cap in respect to use, shape, appearance, etc., and which, unlike the conventional cap, is capable of being conveniently folded and packed when not in use.

Second, to provide in a style of cap worn by uniform men, novel means for attaching an ornament in front such that the ornament and the front section of the cap above the visor is kept in an approximately upright position or collapsed so that the ornament and cap lie flat (for packing).

Briefly, the invention comprises a stiffener inside the collapsible cap to which the cap ornament is attached, the stiffener being free at its lower end so that when the cap is not worn, the stiffener and ornament fall forward and the crown collapses upon a soft head band but when the cap is worn the stiffener and ornament and the front of the cap are forced and maintained in upright position by the pressure of the forehead against the headband, the lower end of the stiffener being inside the sweat band.

The objects and advantages of the invention will be further understood from the following detailed description and from the accompanying drawing, wherein—

Figures 1 and 2 are views, in perspective and side elevation respectively, of a conventional military type cap;

Figure 3 is a side view, partly in elevation and partly in section, of a similar type cap embodying the invention;

Figure 4 is a longitudinal vertical sectional view of the improved cap, the latter being shown in a collapsed state;

Figure 5 is a view of a cap embodying a modification of the invention.

The conventional military cap of the type represented in Figures 1 and 2 consists, briefly, of a slightly oval crown 1 joined to a head band 2 by flare portion or quarters 3 so that the height of the cap is greater at the front than at the rear, both measurements being outside from top of lower welt on the band. The flare or quarters are stiffened in front with extra cloth reinforced by upright steel stays and an eyelet is provided

on the front center line of cap midway between the upper welt on band and edge of crown to receive screw post of cap ornament 4. The top of the cap is slack, the crown falling to the rear without stiffening. A steel grommet or circular-shaped wire (not shown) is fitted into the edge of the crown to maintain the shape of the top. On the outside of the head band at the front of the cap are provided a visor 5 and a sliding chin strap 6. Felled in the cap on the inside of the head band is a sweat leather 7.

Because of its non-collapsible construction and its high front end, the conventional type military cap does not, under the exigencies of the service, lend itself readily to stowing or packing and extreme care must be taken to prevent the cap from being injured or crushed out of shape. These disadvantages are avoided by the improved cap of the present invention which provides a military cap with no substantial stiffness or rigidity anywhere except in the visor and the ornament supporter and which when worn or handled presents the same appearance in all respects as the conventional military cap (less grommet) but which can be folded flat or rolled on the visor without injury to the cap.

The improved cap, shown in Figures 3 to 5 inclusive, is without any grommet in the edge of the crown 1a and a special stiffener 8 is substituted for the front stiffening construction characteristic of the conventional cap. The stiffener 8 preferably consists of a stay piece 8 of steel or other rigid material located on the inside of the cap at the front portion thereof to extend, when in upright position, above and below the upper edge 9 of the soft head band 2a, with its upper portion bridging the eyelet 10 and its lower portion disposed between the head band and the sweat leather 1a, as shown. The upper portion of the stay is perforated to receive the screw post 10 of the cap ornament 4a to which it is secured by means of the usual milled nut 11. The stay may be of any suitable shape or size and purposely is free of any attachment at its lower portion to the cap in order that by reason of its own weight and the weight of the ornament at the upper end it will, in the absence of any restraining force, fall forward to dispose the ornament and the front portion of the crown or quarter 3a in a prone position above the visor 5a with the crown collapsed upon the soft head band, as shown in Figure 4. The ornament and cap thus lie flat for convenient stowage or packing.

In the cap construction shown in Figure 3, the stiffener 8, ornament 4a and the front of the cap

is maintained in upright position when the cap is worn, by the pressure of the forehead against the head band at the lower portion of the stiffener or stay piece 8 and the ornament and front portion of the cap automatically and by reason of the heavier weighted upper end of the stiffener fall into prone position. The upper edge 9a of the head band serves as a fulcrum support upon which the stiffener 8 pivots or turns when moving to and from upright position. The sweat leather 1a of the head band has sufficient "give" when the cap is not worn, to permit the lower end of the stiffener to swing clear of the head band and upwardly for collapsing the cap as hereinbefore described.

The cap shown in Figure 5 differs from the cap construction illustrated in Figures 3 and 4 only in the addition to the head band 2b of a narrow strip or band 12 of stiff material behind which a lower portion of the stay or stiffener 8b can be placed to hold the stiffener and the ornament upright when the cap is not worn. As shown, the material 12 is preferably located on the inside lower portion of the sweat leather 1b and stiffens the leather to maintain the front stiffener 8b in upright position under ordinary handling, being at the same time sufficiently yieldable to applied force or manual manipulation to release the stiffener for collapsing the cap.

From the foregoing it is apparent that the invention provides a collapsible military type cap having a neat swanky appearance when worn and which affords adequate protection against wind, rain, sun, cold, etc., and which can be conveniently folded and packed when not in service.

Various changes and modifications in respect to size, construction, and design of the cap may be made within the scope of the appended claims.

What is claimed is:

1. A collapsible military cap having in combination a head band provided with an unstiffened crown of flexible material and a visor, a sweat band inside of the head band, an ornament on the outside of the front portion of the crown, a rigid ornament supporting member inside the said front portion of the crown and extending down inside the sweat band, said member being attached at its upper end to the ornament and being free at its lower end whereby it can be turned on the edge of the head band to and from upright position from and to a flat position for correspondingly disposing ornament and front portion of the cap.

2. A collapsible military type cap having, in combination, a soft head band provided with a collapsible crown, an ornament for the outside of the front portion of the crown, and a stiffening member on the inside of the front portion of the crown and secured at its upper end to the said ornament, said stiffener being free at its lower end so that when the cap is not worn the stiffener and ornament are adapted of their own weight to assume a prone position with the crown collapsed upon the head band, the said stiffener and ornament and front portion of the cap automatically being forced into upright position by the pressure of the forehead of the wearer against

the lower end of the stiffener when the cap is worn.

3. A collapsible military type cap having in combination, a soft head band provided with a sweat leather and a collapsible crown, an ornament for the outside of the front portion of the crown, and a front-stiffening member on the inside of the said front portion of the crown and secured at one end to the said ornament, said member being of a length to extend at its other end inside the sweat leather and being free at said other end so that when the cap is not worn the stiffener and ornament are adapted by their own weight to assume a prone position with the crown collapsed upon the head band, the said 15 stiffener and ornament and front portion of the cap automatically being forced into upright position by the pressure of the forehead of the wearer against the sweat leather at the free end of the stiffening member when the cap is worn.

4. A collapsible military type cap having, in combination, a soft head band provided with a visor and a collapsible crown, an ornament for the outside of the front portion of the crown above the visor, a rigid stay piece on the inside of the cap at the front thereof and extending above and below the upper edge of the hat band to provide a stiffening member for the said front portion of the crown, said member having the said ornament secured thereto and being otherwise free so that when the cap is not worn the stay piece by reason of its own weight and the weight of the ornament at the upper end is adapted to pivot on the upper edge of the head band as on a fulcrum to dispose the ornament and the front portion of the crown in a prone-position over the said visor, the said stay piece and ornament and front portion of the cap automatically being returned to and maintained in upright position by the pressure of the forehead of the wearer against the free end of the stay piece when the cap is worn.

5. A collapsible military cap having, in combination, a head band provided with a sweat leather and a collapsible crown with a flat top 45 inclined to the head band so as to be higher at the front of the cap than at the rear, an ornament for the outside of the front portion of the crown, a front stiffening member on the inside of the cap and extending above and below the upper 50 edge of the head band with its upwardly extending portion secured to the ornament and with its lower extended portion disposed between the head band and the sweat leather, said sweat leather having a stiffened portion adapted to bear 55 against the lower end of the front stiffening member to hold the member and the ornament and the front portion of the cap in upright position, said member upon displacement of the stiffened portion of the sweat leather relative to the 60 lower end of the member being free to fall forward on the upper edge of the head band as a fulcrum to collapse the crown with the said stiffener, ornament and front portion of the cap in a 65 prone position.

BYRON QUINBY JONES.
